REFINING PROCESS, INCLUDING REGENERATION OF ALKALINE TREATING AGENTS

Charles H. Brooks, Swarthmore, Pa., assignor to Sun Oil Company, Philadelphia, Pa., a corporation of New Jersey

Application May 9, 1955, Serial No. 506,958

9 Claims. (Cl. 196—32)

This invention relates to the regeneration of alkaline treating agents containing alkali metal mercaptides or inorganic sulfides.

It is known in the art to electrolytically regenerate caustic soda which has been used in the treatment of mineral oil fractions. Such regeneration may be accomplished by passing the used caustic soda through an electrolytic cell to which electric current is supplied at a suitable voltage. The water in the caustic soda is electrolyzed, oxygen and hydrogen being thereby formed. The oxygen reacts with the sodium mercaptides to form disulfides, or with sodium sulfide to form free sulfur or other products. The disulfides can be subsequently separated from the caustic soda, for example by extraction with naphtha. In the subsequent discussion, reduction in mercaptide content will be discussed, though it is to be understood that the invention also applies to reduction in inorganic sulfide content.

Electrolytic regeneration provides an advantageous reduction in mercaptide content of used caustic soda, but has the disadvantage that the amount of electricity required to reduce the mercaptide content by a given increment increases as the mercaptide content decreases, so that it may not be feasible to remove as much of the mercaptide content of the used caustic as desired without encountering the necessity of using excessive amounts of electricity. The present invention provides a manner in which large reductions in mercaptide content can be obtained without using excessive amounts of electricity.

According to the present invention, used caustic is first partially regenerated electrolytically, then contacted with an epoxide reagent to react with mercaptides remaining in the caustic after the electrolytic regeneration. The treatment with epoxide efficiently reduces mercaptide content at levels of initial mercaptide content which are too low to permit efficient oxidation by electrolytic oxygen. The invention thus permits electrolytic regeneration to be used at the higher levels of initial mercaptide content, at which the electrolytic regeneration is satisfactorily efficient, while using epoxide treatment subsequently when the mercaptide content is lower. The process of the invention can be applied to used alkaline treating agents which contain inorganic sulfide, mercaptides, or both.

The electrolytic regeneration can be conducted according to any of the known procedures for such regeneration. Thus, for example, the procedures disclosed in United States Patent No. 2,654,706, issued October 6, 1953, to Peter J. Gaylor can be employed. Any of the known methods of separating disulfides from the regenerated treating agent can be employed.

The epoxide regeneration is performed by contacting the used treating agent with an epoxide capable of reacting with the mercaptides and sulfides in the treating agent. The temperature may be ordinary room temperature or higher or lower temperatures, e. g. 30° F. to 300° F. Preferred epoxides are those having the formula

2

where R is selected from the group consisting of hydrogen, halogen radicals, hydrocarbon radicals having 1 to 5 carbon atoms, phenoxyalkyl radicals having 7 to 10 carbon atoms, alkoxyalkyl radicals having 2 to 10 carbon atoms, and

radicals, and where R', R'' and R''' are each selected from the group consisting of hydrogen, hydrocarbon radicals having 1 to 5 carbon atoms, and halogen radicals. More preferred epoxides are those having the formula

where R is selected from the group consisting of hydrogen and alkyl radicals having 1 to 2 carbon atoms. Examples of suitable epoxides are ethylene oxide, propylene oxide, butylene oxide, styrene oxide, phenoxy propylene oxide, butoxy propylene oxide, epichlorohydrin, butadiene oxide, etc.

The alkaline treating agent can have been used to refine any of various petroleum materials, e. g. crude oil, reduced crude, kerosene, spirits, gasoline, gas oil, furnace oil, diesel fuel, jet fuel, lubricating oil, natural gas, refinery gas, liquefied petroleum gases, etc., and may contain materials such as phenolates and naphthenates in addition to mercaptides or inorganic sulfides.

Preferably, according to the invention, the electrolytic regeneration brings about more than half of the total reduction in mercaptide content obtained by the combination of electrolytic and epoxide regeneration. More preferably, the electrolytic regeneration brings about more than three-fourths of the total reduction in mercaptide content. The electrolytic regeneration in some instances works with satisfactory efficiency until nearly all of the mercaptide content has been eliminated, leaving only a small amount, e. g. 1 to 10 weight percent of the original mercaptide content (in grams per liter) to be removed by epoxide treating.

In one embodiment of the invention, used caustic soda containing mercaptides and inorganic sulfides is contacted with epoxide to effect reaction thereof with inorganic sulfides, mercaptides being left in the caustic, which is then electrolytically regenerated to remove part of the remaining mercaptides; the resulting caustic is again contacted with an epoxide to remove at least part of the mercaptides remaining after the electrolytic regeneration. This operation has the advantages that inorganic sulfides are removed prior to the electrolytic regeneration, thus avoiding possible ill effects from electrolytic action on the sulfides to produce sulfates and other undesirable products, and that electrolytic action is used to remove part of the mercaptides under circumstances which produce satisfactory efficiency of removal, epoxide being used thereafter to remove mercaptides under circumstances which would not produce satisfactory efficiency in an electrolytic regeneration.

The reaction of epoxides with caustic containing mercaptides and inorganic sulfides can be made selective with regard to inorganic sulfides. Thus, by limiting the extent of reaction of epoxide with materials in the caustic, the amount of inorganic sulfide reacted relative to the amount of mercaptide reacted can be maximized. Conditions limiting the extent of reaction include small amounts of epoxide, short treating times, low temperatures, etc. In the light of the present specification, a person skilled in the art can choose suitable conditions.

In the epoxide regeneration of treating agents containing alkali metal sulfides and mercaptides, the following

represent the principal reactions, ethylene oxide being the epoxide for purpose of illustration:

Reaction No. 1 proceeds considerably more readily than Reaction Nos. 2 and 3. Reaction No. 2 probably proceeds slightly more readily than Reaction No. 3. The use of small amounts of epoxide, short contacting times and low temperatures tends to result in Reaction No. 1 proceeding to the exclusion of the other two.

In the electrolytic regeneration of treating agents containing alkali metal mercaptides and hydroxyalkyl mercaptides formed in preceding epoxide regeneration, the following are the principal reactions:

Thus the products obtained include dihydrocarbon disulfides, diethanol disulfide, and monoethanol monohydrocarbon disulfides. The dihydrocarbon disulfides are the least soluble in the caustic and therefore the most readily recoverable therefrom, e. g. by extraction with a hydrocarbon solvent. The diethanol disulfide is the most soluble in the caustic and can advantageously be left therein to function as a solutizer in subsequent use of the caustic to remove mercaptans from the hydrocarbons. The monoethanol monohydrocarbon disulfides are intermediate in solubility; they as well as the dihydrocarbon disulfides can be removed from the caustic, or they can be left in the caustic if desired.

The invention will be further described with reference to the attached drawing. Figure 1 illustrates a combined electrolytic and epoxide regeneration according to the invention and Figure 2 illustrates a process wherein two treating stages are employed, with epoxide regeneration of the alkaline treating agent after the first stage and a combined electrolytic and epoxide regeneration after the second stage.

In Figure 1, sour hydrocarbons, e. g. H₂S-free straight run gasoline containing mercaptans, are introduced into mercaptan removal zone 10 where they are contacted with an aqueous solution of caustic soda. The strength of the caustic and the treating conditions can be those which are used in conventional caustic treating for mercaptan removal. The used caustic containing sodium mercaptides is electrolytically partially regenerated in zone 11, the conditions being chosen to effect only partial reduction of the mercaptide content of the caustic. Disulfides formed during the electrolytic regeneration are removed according to conventional procedure in disulfide removal zone 12. The partially regenerated caustic is then contacted with an epoxide, e. g. ethylene oxide, in zone 13 in order to react the epoxide with mercaptides remaining in the caustic after the electrolytic regeneration. The reaction may be carried out for example at room temperature with agitation followed by standing for one hour. 1 to 5 moles of epoxide per mole of mercaptides may be employed for example, and preferably at least 1.5 moles. The regenerated caustic containing hydroxythioether reaction products is withdrawn from zone 13 and can be used to contact additional sour hydrocarbons. If desired hydroxythioethers can be extracted from the caustic

before such use by means of a hydrocarbon solvent, e. g. petroleum naphtha, pentane, etc.

The electrolytic and epoxide regenerations combine to produce a reduction in mercaptide content to a suitable level, the efficiency of the reduction being greater than that which could be obtained with electrolytic regeneration alone to that level.

In another embodiment, where for example the hydrocarbons contain H₂S as well as mercaptans, instead of directly introducing used caustic from zone 10 through line 15 into electrolytic regeneration zone 11, the used caustic can be introduced through line 16 into epoxide regeneration zone 14 where it is partially regenerated by contact with an epoxide, e. g. ethylene oxide. The amount of epoxide used is generally within the approximate range from 1 to 5 moles of epoxide per mole of inorganic sulfide in the caustic. If substantially complete removal of inorganic sulfide from the caustic is desired, the amount of epoxide is preferably at least 1.5 moles per mole of inorganic sulfide. If conversion of inorganic sulfide to dialkanol sulfide is desired, the amount of epoxide is preferably at least 3 moles per mole of inorganic sulfide. If minimization of mercaptide reaction with epoxide is desired, the amount of epoxide is preferably not greater than 2, more preferably not greater than 1.5 moles of epoxide per mole of inorganic sulfide. The above proportions apply generally to epoxides having only one epoxy group; epoxides having more than one epoxy group can be used in correspondingly less amounts.

30 The amount of epoxide to be used to achieve a given purpose may vary depending on the other conditions; e. g. short contacting times, low temperatures, etc. are factors which, like small amounts of epoxide, tend to limit the extent of reaction of epoxide with constituents of the caustic.

35 The caustic from zone 14 is introduced through line 17 into electrolytic regeneration zone 11. From this point on, the procedure is generally the same as in the previously described embodiment.

40 In Figure 2, sour hydrocarbons, e. g. straight run gasoline containing both mercaptans and hydrogen sulfide, are introduced into hydrogen sulfide removal zone 20 where they are contacted with an aqueous solution of caustic soda under conditions producing removal of hydrogen sulfide, the removal of mercaptans being minimized. In the light of the present specification, a person skilled in the art can select the conditions to obtain this result, the reaction of sodium hydroxide with hydrogen sulfide occurring more readily than that of sodium hydroxide with mercaptans.

45 The used caustic containing sodium sulfide is contacted in zone 21 with an epoxide, e. g. ethylene oxide, the contacting being performed for example at room temperature with agitation followed by standing for one hour.

50 Three moles of ethylene oxide per mole of sodium sulfide may be employed for example, in order to convert sodium sulfide to diethanol sulfide.

55 The regenerated caustic containing the diethanol sulfide formed in the regeneration is passed through lines 26 and 27 and used in zone 22 to treat the sour hydrocarbons from which hydrogen sulfide was removed in zone 20. The diethanol sulfide acts as a solutizer to increase the solubility of mercaptans in the caustic. Caustic containing sodium mercaptides is passed from zone 22 to zone 23 where it is electrolytically partially regenerated to convert mercaptides to disulfides, the latter being removed in disulfide removal zone 24. The caustic is then contacted with an epoxide, e. g. ethylene oxide, in zone 25 to react with mercaptides remaining after the electrolytic regeneration. The conditions in the regeneration in zone 25 can be, for example, generally the same as those in the regeneration in zone 13 of Figure 1.

60 If the epoxide-regenerated caustic from zone 21 contains hydroxyethyl mercaptides as well as diethanol sulfide, the hydroxyethyl mercaptides undergo, during elec-

trolytic regeneration, Reactions 5 and 6 as set forth earlier in the specification.

Instead of removing mainly H_2S in zone 20, removal of H_2S and partial removal of mercaptans can be effected in zone 20, and caustic containing sodium sulfide and mercaptides recycled through lines 31 and 28 to contact additional sour hydrocarbons containing hydrogen sulfide and mercaptans. The presence of mercaptides in the caustic greatly inhibits removal of mercaptans from the sour hydrocarbons in the caustic, but highly effective removal of hydrogen sulfide can be obtained in spite of the presence of sodium sulfide in the caustic. A drag stream from the circulating caustic is introduced through line 29 into regeneration zone 21 wherein it is contacted with an epoxide, e. g. ethylene oxide. Preferably 1 to 5 moles of epoxide are employed per mole of sodium sulfide. More preferably, at least 1.5 moles of epoxide per mole of sulfide are used, and sulfide is substantially completely converted, part probably being converted to hydroxyethyl mercaptide and part to diethanol sulfide. Sodium mercaptides are only partially converted to hydroxythioethers. If minimization of mercaptide reaction with epoxide is desired, preferably not more than 2, and more preferably not more than 1.5, moles of epoxide per mole of alkali metal sulfide are employed. On the other hand, if conversion of alkali metal disulfide to dialkanol sulfide is desired, rather than merely to hydroxyalkyl mercaptide, preferably at least 3 moles of epoxide per mole of alkali metal sulfide are employed.

The epoxide-treated caustic is electrolytically partially regenerated in zone 40 to convert part of the remaining sodium mercaptides to disulfides, the latter being removed in zone 30. The partially regenerated caustic is then contacted with an epoxide, e. g. ethylene oxide, in zone 46 to react with mercaptides remaining after the electrolytic regeneration. The caustic is then passed through lines 41 and 27 into zone 22.

Instead of returning caustic to zone 20 through line 31, all of the caustic can be regenerated in zone 21 and a portion returned to zone 20 through lines 26 and 28, a drag stream 42 being taken for electrolytic regeneration.

The caustic introduced into zone 22 through line 27 may contain diethanol sulfide, diethanol disulfide, hydrocarbon disulfides, monohydroxy disulfides, or hydroxythioethers, or mixtures thereof, depending on the previous treatment of the caustic. Various of these materials act as solutizers to increase the solubility of mercaptans in the caustic during the treating in zone 22. Caustic containing sodium mercaptides is passed from zone 22 to electrolytic regeneration zone 23. From this point on, the procedure is generally the same as in the previously described embodiment.

In another embodiment, instead of introducing the treated hydrocarbons from zone 20 through line 43 into zone 22, the treated hydrocarbons can be withdrawn as a product through line 44, and a different sour hydrocarbon charge introduced through line 45 into zone 22. In this embodiment, the charge to zone 20 can be, for example, an essentially mercaptan-free, H_2S -containing hydrocarbon fraction, and the charge to zone 22 an essentially H_2S -free, mercaptan-containing fraction.

The following example illustrates the invention:

A 15% aqueous solution of caustic soda was used to treat straight run gasoline. Various portions of gasoline were treated with the same caustic solution with occasional intervening electrolytic partial regenerations of the solution. After the tenth portion of gasoline was treated, the caustic solution contained 384 mg. of mercaptide sulfur per liter of solution and 615 mg. of inorganic sulfides as H_2S per liter. The solution was electrolytically regenerated by passing through an electrolytic cell at a rate of 70 ml. per minute, the total regeneration time being 70 minutes, the voltage 3.0, the amperage 15, and the temperature 74° F. The mercaptide sulfur content of the regenerated caustic solution

was 333 mg. per liter, and the inorganic sulfide content as H_2S was 249 mg. per liter. The efficiency of the regeneration was 18 percent assuming conversion of mercaptans to disulfides and sodium sulfide to free sulfur.

The regenerated solution, after separation of disulfides therefrom, but without any further treatment, was passed again through the electrolytic cell, the total regeneration time being 62 minutes in this pass, and the conditions being otherwise the same as in the first pass. The mercaptide and sulfide contents were reduced to 224 and 100 respectively, the efficiency being 10 percent. In four subsequent passes through the cell, in each case after separation of disulfides, the conditions being similar to those in the first two passes, the mercaptide contents were reduced to 129, 64, 26 and 19 respectively, the sulfide contents were reduced to 33, 16, 0 and 0 respectively, and the efficiencies were 5, 2, 1 and 0.2 percent respectively, indicating that the cell efficiency decreases as the mercaptide level decreases. The following table summarizes the results:

Pass No.	Mercaptide Sulfur		Inorganic Sulfide as H_2S		Efficiency, percent
	Before	After	Before	After	
25					
1	384	333	615	249	18
2	333	224	249	100	10
3	224	129	100	33	5
4	129	64	33	16	2
5	64	26	16	0	1
6	26	19	0	0	0.2

According to the invention, the caustic solution is, after one or more of the above passes through the electrolytic cell, contacted with an epoxide to effect considerably more efficient reduction of mercaptide content than was obtained at the same mercaptide level in the electrolytic regeneration.

In the preceding description, electrolytic regeneration has been disclosed with reference to electrolysis in the presence of the used caustic soda which is to be regenerated. Electrolytic regeneration as contemplated herein also includes introduction of freshly prepared electrolytic oxygen into the used caustic soda, the electrolysis zone and the regeneration zone being separate but the oxygen from the electrolysis zone being introduced into the regenerating zone directly after its formation.

The invention claimed is:

1. Process for regenerating aqueous solutions of alkali metal hydroxides which have been used to treat petroleum and which contain sulfur compounds selected from the group consisting of inorganic sulfides and mercaptides which comprises: partially regenerating such solution electrolytically; and contacting the partially regenerated solution with an epoxide, thereby to react said epoxide with sulfur compounds remaining unconverted after the electrolytic partial regeneration.
2. Process according to claim 1 wherein a greater reduction in mercaptide content is obtained in the electrolytic regeneration than in the contacting with epoxide.
3. Process for regenerating aqueous solutions of alkali metal hydroxides which have been used to treat petroleum and which contain mercaptides and inorganic sulfides which comprises: partially regenerating such solution by contact with an epoxide, thereby to react said epoxide with inorganic sulfides; further partially regenerating the resulting solution electrolytically; and contacting the resulting solution with an epoxide, thereby to react the latter epoxide with mercaptides remaining unconverted after the electrolytic regeneration.
4. Process for refining petroleum fractions which comprises: contacting a petroleum fraction containing hydrogen sulfide with an aqueous solution of an alkali metal hydroxide; contacting the resulting solution containing alkali metal sulfide with an epoxide, thereby to react said epoxide with said alkali metal sulfide; contacting a

petroleum fraction containing mercaptans with the epoxide-treated solution; partially regenerating electrolytically the resulting solution containing alkali metal mercaptides; and contacting the partially regenerated solution with an epoxide, thereby to react said epoxide with mercaptides remaining unconverted after the electrolytic regeneration.

5. Process according to claim 4 wherein a petroleum fraction containing hydrogen sulfide and mercaptans is the charge to the first-named contacting, and the petroleum fraction product from the first-named contacting is the charge to the third-named contacting.

6. Process for refining petroleum fractions which comprises: contacting a petroleum fraction containing hydrogen sulfide and mercaptans with an aqueous solution of an alkali metal hydroxide; regenerating the resulting solution by means of an epoxide to remove alkali metal sulfides and mercaptides therefrom; contacting a petroleum fraction containing mercaptans with the regenerated solution; partially regenerating electrolytically the resulting solution containing alkali metal mercaptides; and contacting the partially regenerated solution with an epoxide, thereby to react said epoxide with mercaptides remaining unconverted after the electrolytic partial regeneration.

7. Process for refining petroleum fractions which comprises: contacting a petroleum fraction containing hydrogen sulfide and mercaptans with an aqueous solution of an alkali metal hydroxide; contacting the resulting solution containing alkali metal sulfide and alkali metal mercaptide with an epoxide to convert alkali metal sulfide; using the resulting treating agent to contact additional petroleum hydrocarbons containing hydrogen sulfide and

mercaptans to remove hydrogen sulfide therefrom; contacting the resulting solution containing alkali metal sulfide and alkali metal mercaptide with an epoxide to convert alkali metal sulfide; partially electrolytically regenerating the resulting solution to convert alkali metal mercaptides; and contacting the resulting solution with an epoxide to convert alkali metal mercaptides remaining after the electrolytic regeneration.

8. Process for refining petroleum fractions which comprises: contacting a petroleum fraction containing hydrogen sulfide and mercaptans with an aqueous solution of an alkali metal hydroxide; contacting the resulting solution containing alkali metal sulfide and alkali metal mercaptide with a petroleum fraction containing hydrogen sulfide and mercaptans to selectively remove hydrogen sulfide; contacting the resulting solution containing alkali metal sulfide and alkali metal mercaptide with an epoxide to convert alkali metal sulfide; partially electrolytically regenerating the resulting solution; and contacting the resulting solution with an epoxide to convert alkali metal mercaptide remaining after the electrolytic regeneration.

9. Process according to claim 8 wherein, after the last-named contacting, the resulting solution is contacted with the petroleum fraction from which hydrogen sulfide was selectively removed, thereby to remove mercaptans.
